THOMAS DOLAN, OF PHILADELPHIA, PENNSYLVANIA.

Design No. 3,196, dated September 22, 1868.

DESIGN FOR THE LOWER PORTION OF A GORED SKIRT.

The Schedule referred to in these Letters Patent and making part of the same.

TO ALL WHOM IT MAY CONCERN:

Be it known that I, THOMAS DOLAN, of the city and county of Philadelphia, State of Pennsylvania, have invented or produced a new and original Design for the Lower Portion of a Gored Skirt; and I do hereby declare that the accompanying drawing, and the following explanation thereof, form a full, clear, and exact description of the said design.

The figure in the drawing represents part of a gored skirt, A being a portion of the body, and B a portion of the border.

The body is of woven fabric, substantially of the style shown, and the border is composed of a series of parallel zigzag ribs, arranged in a manner too clearly shown in the drawing to need description.

Irrespective of the colors employed, I claim—

The design for the lower portion of a gored skirt, substantially as described, and represented in and by the accompanying drawing.

In testimony whereof, I have signed my name to this specification in the presence of two subscribing witnesses.
